UNITED STATES PATENT OFFICE.

ARTHUR P. WILDER, OF ARLINGTON, AND AUGUSTINE P. FAY, OF ROXBURY, MASSACHUSETTS.

TURN SHOE.

Application filed September 27, 1923. Serial No. 665,184.

This invention relates to turn shoes.

In a turn shoe, the counter usually terminates at the forward edge of the heel seat so that the upper leather in the shank portion is unsupported and, consequently, is weak and provides but little support for the foot. Due to the weakness at this point, the upper leather may flex outwardly or buckle in an unsightly manner as the shoe is flexed in walking.

An object of this invention is to provide a turn shoe with means to provide support for the upper at the arch-portion of the shoe, whereby to remove the above-enumerated objections and also to provide support for the arch of the foot.

A further object is to provide a turn shoe having a shank piece formed with a lateral extension adapted to bear against the upper on the inner side of the shoe at the shank portion thereof and support it and prevent the formation of wrinkles and fullness which ordinarily occurs at this point.

The inner lining of a turn shoe is usually full and loose and may have wrinkles therein at the shank portion of the shoe for the reason that the lining is on the outside of the shoe before the turning operation and consequently is longer than the upper. A further object of the invention, consequently, is the provision of means, and, more specifically, means associated with the shank piece of the shoe, to remove the fullness of the lining at the instep of the shoe.

A yet further object of the invention is the provision of a shank piece for a turn shoe having imbedded therein a shank stiffener, as a stiff yet flexible metal strip.

A yet further object is generally to improve the construction, and methods of manufacture, of turn shoes.

Fig. 1 is a perspective view of a turn shoe cut away to illustrate the invention.

Fig. 2 is a plan view of a portion of a turn shoe arranged in readiness to receive the shank piece.

Fig. 3 is a view similar to Fig. 2 but with the shank piece in position in the shoe.

Fig. 4 is an enlarged sectional detail illustrating the manner in which the inner lining is secured to the shank piece.

Fig. 5 is a plan view of the shank piece.

Fig. 6 is a reverse plan view of the shank piece and illustrating more particularly the shank stiffener therein.

Fig. 7 is a reduced cross-section taken along line 7—7 of Fig. 5.

As here shown, the turn shoe embodying the invention may be of more or less usual construction and comprise the sole 10, the upper 11, and the inner lining 12. The upper and inner lining may be sewed to the sole by the stitching 13.

The upper of a turn shoe usually is weak and has a tendency toward fullness, or wrinkles, at the inner side of the shoe, in the shank portion thereof and just to the rear of the ball-portion of the shoe, as indicated at A. The inner lining 12, in about the same place, or at B, also has a tendency toward fullness, or wrinkles for the reason that the shoe is lasted inside out and with the lining outermost; and the lining is consequently longer than the upper.

This invention provides means to support the upper at A and substantially prevent the formation of wrinkles in the upper at this point; and also means to arrange the inner lining 12 in such a manner that the fullness thereof is eliminated and the lining caused to be tight and snug in the shoe. In its preferred form, the means by which these results are accomplished consists in an improved shank piece 15.

Said shank piece 15 may have the heel portion 16 and the fore, or ball, portion 17 and of such shape as to fit within the shoe, in the usual manner. In accordance with this invention, however, said shank piece is formed or provided with a lateral extension 18 of more or less arcuate form, which extension is adapted to project laterally from that portion of the shank piece which is adapted to lie along the inner side of the shoe; and said extension may be contiguous with the forward edge of the shank piece and extend rearwardly toward and terminate at about the heel-portion 16 of the shank piece.

In the manufacture of the turn shoe embodying the invention, the lining at the shank portion of the shoe is left free and is turned back from the stitching line during the sewing operation so that, while the line of stitching passes through both the lining and upper in front of the ball-portion of the shoe as in Fig. 3, it passes beneath and free from the lining at the shank portion of the shoe, as is best illustrated in Fig. 2. For this purpose of readily sewing the shoe, the lining may be formed or provided with a

small slit 20 therein, which slit may be located in the lining in the vicinity of the ball-portion of the shoe and extend from the margin of the lining inwardly a sufficient 5 distance to permit the lining to be turned back from the stitching line. If the shoe is sewed around the heel seat, a similar slit, not herein shown, may be provided in the lining adjacent the heel seat; or, if the 10 stitching stops at the heel seat, the rear slit may not be necessary.

After the shoe is sewed, it is turned, and the unattached portion of the lining at the shank-portion may be drawn snug and secured 15 in position. Preferably, the lining is secured to the shank-piece and, for this purpose, said shank piece is or may be forced or provided with a channel 22 in the upper face thereof in that portion adapted to lie along 20 the inner side of the shoe, and at the base of the lateral extension 18 of the shank piece.

The free portion of the lining is placed over the lateral extension of the shank piece and the bottom edge of said lining is tucked 25 into said channel 22. The lining is drawn tight against the lateral extension 18 and also the upper, and secured in said channel in a suitable manner, as by the use of an adhesive preferably the lining is also secured to 30 the body of said lateral extension. The usual lining may then be placed to cover the sole of the shoe and the body of the shank piece.

The lateral extension 18 of said shank 35 piece, in addition to functioning to remove the wrinkles and keep taut the upper in the shank portion of the shoe, is designed to serve as an arch-support for the foot, said extension being disposed in the shoe in a 40 position to engage the arch.

Preferably said lateral extension 18 may be treated in a suitable manner as by a glue or size to render it relatively stiff. The extension may be tempered as by immersing it 45 in water, to render it flexible for the re-lasting operation of the turn shoe and, when the shoe is re-lasted and the stiffening agent in the extension has become dry and hard, the extension will be conformed to and retain 50 the shape of the last and be relatively stiff and thereby provide increased support for the shoe upper, and also for the foot.

The reverse face of the shank-piece may be provided with a channel 25 extended from 55 the heel-portion into or adjacent the forward or ball-portion thereof, and a relatively stiff, yet flexible, strip, preferably of steel, and comprising a shank-stiffener, may be disposed in said channel and thereby embedded 60 in the shank piece. Rivets 27 may be passed through said stiffener and the shank piece, thereby to connect the two positively. The lips 28 of said channel are adapted substantially to cover the stiffener. This arrangement has an advantage in that the

lower or reverse face of the shank-piece may thereby be more or less flat and may also have a greater surface on which glue can take hold than is the case with the usual form of shank stiffener externally applied. 70

The structure may be otherwise modified without departing from the spirit of the invention.

We claim:

1. A turn shoe having an upper, an inner lining, and sole, and a line of stitching passed through the upper and sole and under and free from the lining at the shank-portion of the shoe, thereby leaving the lining free and un-attached at the shank-portion, 80 said line of stitching being passed through the upper and sole, and also through the lining, beyond the shank-portion.

2. A turn shoe having an upper, an inner lining, and sole, and a line of stitching passed through the upper and sole and under and free from the lining at the shank-portion of the shoe, thereby leaving the lining free and un-attached at the shank-portion, 90 said line of stitching being passed through the upper and sole, and also through the lining, beyond the shank-portion, and other means securing the free portion of the lining to the shoe.

3. A turn shoe having an upper, inner lining and sole, a shank piece disposed within said shoe, means to attach the upper and a portion of the inner lining to the sole and leave free that portion of the inner lining disposed at the shank-portion of the shoe, and other means to attach said free portion of the inner lining to said shank piece only. 100

4. A turn shoe having an upper, inner lining and sole, a shank piece disposed within the shoe, a line of stitching passed through the sole, the upper and a portion of the inner lining and passed beneath that portion of the inner lining disposed at the shank-portion of the shoe, whereby to leave 110 said portion free, and means to secure said free portion of the inner lining to the shank piece only.

5. A turn shoe having an upper, inner lining, and sole, a shank piece disposed within the shoe having a channel in its upper face at the shank-portion of the shoe and means to secure the inner lining to the sole and leave free a portion of the lining at the shank-portion of the shoe, said free portion of the lining being received and secured in the channel of said shank piece. 115

6. A turn shoe having an upper, inner lining and sole, a shank piece disposed within the shoe and having a channel in its upper face at the shank portion of the shoe, and a line of stitching passed through the sole, the upper and a portion of the inner lining and passed beneath that portion of the inner lining disposed at the shank por- 120 125 130

tion of the shoe whereby to leave said portion free, said free portion of the lining being received and secured in the channel in said shank piece.

5 7. A turn shoe having an upper, inner lining, sole, and shank piece, said shank piece having a lateral extension disposed between the inner lining and upper and extended upward along said upper at the shank 10 portion of the shoe, said inner lining at said lateral extension having means to secure it to said shank-piece only.

8. A turn shoe having an upper, inner lining and sole, a shank piece disposed within said shoe and having a lateral extension disposed between said lining and upper and extended upwardly along said upper at the shank-portion of the shoe, said shank-piece having a channel formed therein at about 20 the junction of said lateral extension and shank piece, and said portion of the inner lining extended over said lateral extension and disposed and secured in said channel.

9. A turn shoe having an upper, inner 25 lining, and sole, a line of stitching passed through said sole, upper and a portion of said inner lining and passed beneath that portion of the inner lining disposed at the shank-portion of the shoe, whereby to leave 30 said portion free, and a shank piece disposed within the shoe and having a lateral

extension extended beneath the free portion of said inner lining and upwardly along the upper, said shank piece also having a channel at its junction with said lateral 35 extension in which the free portion of said inner lining is received and secured.

10. The method of manufacturing turn shoes which consists in lasting the shoe inside out, securing over the heel and shank 40 portions of the shoe a shank piece having a temporarily-tempered lateral-extension, turning the shoe and relasting it and allowing said tempered lateral-extension to set and harden, whereby to be conformed to and 45 retain the shape of the last.

11. The method of making shoes characterized by having a lateral-extension disposed within the shoe at the shank portion thereof and extended upwardly and lying 50 along the upper at the shank portion, said method consisting in tempering the lateral-extension, whereby to render it flexible, lasting the shoe and tempered lateral extension, and allowing the lateral extension to set and 55 stiffen, whereby to be conformed to and retain the shape of the last.

In testimony whereof, we have signed our names to this specification.

ARTHUR P. WILDER.
AUGUSTINE P. FAY.
